STAPLING MACHINE OR SIMILAR ARTICLE

Henry Ruskin, Bayside, N.Y., assignor to Swingline, Inc.,
Long Island City, N.Y., a corporation of New York

Application April 21, 1958, Serial No. 50,557

Term of patent 14 years

(Cl. D74—1)

Fig. 1

Fig. 2

Fig. 3

Fig. 4

Fig. 1 is a side perspective view of a stapling machine showing my new design;

Fig. 2 is a top plan view of the base portion thereof, the top having been omitted for clarity of illustration;

Fig. 3 is a side elevational view, the side opposite thereto being similar in appearance; and

Fig. 4 is a sectional view thereof taken on the line 4—4 of Fig. 2.

The characteristic feature of my design resides in the shape of the anvil which is curved and partially overlies the front portion of the base of the stapling machine as clearly shown in Fig. 1 of the drawings.

I claim:

The ornamental design for a stapling machine or similar article, as shown and described.
